PERMANENT HAIR WAVING APPARATUS

Humberto Garcia (Rendón), Mexico City, Mexico

Application December 22, 1950, Serial No. 202,359

3 Claims. (Cl. 132—39)

1

This invention relates to new and useful improvements and structural refinements in permanent hair waving apparatus, and the principal object of the invention is to efficiently wave human hair so as to resemble natural waves.

The two most common systems of hair waving are the spiral type and the croquignole. In the spiral type the hair is wound along rod shaped devices with the winding commencing at the root of a strand of hair and finishing at the loose end. On the other hand, in the croquignole type the hair is wound inwardly from the loose ends to the roots.

The instant invention differs substantially from the above outlined types of waving, insofar that it employs novel structural means whereby a strand of hair may be wound or coiled in a series of curls which have their axes disposed substantially at right angles to each other, thus achieving a highly novel and realistic result.

Some of the advantages of the invention reside in its simplicity of construction, in its efficient operation, and in its adaptability to economical manufacture.

With the above more important objects and features in view and such other objects and features as may become apparent as this specification proceeds, the invention consists essentially of the construction and arrangement of parts as shown in the accompanying drawings, in which:

Figure 1 is a top plan view of the invention;

Figure 2 is a side elevational view thereof;

Figure 3 is an end view of the same;

Figure 4 is a perspective view of the clamp used in the invention, the clamp being shown in its open position;

Figure 5 is a perspective view of the hair curling member used in the invention;

Figure 6 is a view showing the manner whereby a strand of hair is wound on the member shown in Figure 5;

Figure 7 is a perspective view of a modified hair curling member;

Figure 8 is a perspective view of a further modified hair curling member;

Figure 9 is a perspective view of a still further modified hair curling member;

Figure 10 is a transverse sectional detail, taken substantially in the plane of the line 10—10 in Figure 9;

Figure 11 is a view showing whereby a strand of hair is wound around the curling member shown in Figure 9;

Figure 12 is a perspective view of a still further modified hair curling member;

2

Figure 13 is a transverse sectional detail, taken substantially in the plane of the line 13—13 in Figure 12;

Figure 14 is a fragmentary exploded perspective view of the hair curling member shown in Figure 12;

Figure 15 is a group perspective view of a still further modified embodiment of the invention;

Figure 16 is a side elevational view, partly in section, showing the embodiment of Figure 15 assembled; and

Figure 17 is a group perspective view of a stud and spring used in the embodiment of Figures 15 and 16.

Like characters of reference are employed to designate like parts in the specification and throughout the several views.

Referring now to the accompanying drawings in detail, and more particularly to Figures 1-6, 20 inclusive, the invention consists of a hair curling apparatus which is designated generally by the reference character 20 and embodies in its construction two major sub-assemblies, namely, a hair strand receiving clamp 22 and a hair curling member 24 which is separably attached to the clamp.

It may be explained at this point that several of the hair curling members 24 may be associated with each clamp 22, and several modified embodiments of the hair curling members are provided, which may be used selectively with the same clamp.

The clamp 22 is more-or-less of conventional nature, including a pair of pivotally connected arms 26, 28 which are provided with rubber sleeves 30 and are swingable toward and away from each other about their common pivot 32, while conventional locking means 34 are employed for retaining the clamp in its closed position wherein a strand of hair is frictionally engaged, at the roots thereof, by the rubber sleeves 30 of the two arms 26, 28.

The one or more hair curling members 24 which are employed with the clamp 22 are identical in construction, each comprising an elongated, tubular body 36 and a plurality of tubular buttons 38 which are secured by suitable rivets 40 to the body 36, the buttons 38 being spaced longitudinally on the body and extending radially therefrom in a common plane, as shown. The rivets 40 extend through the body 36 as well as through the buttons 38 and serve to secure enlarged heads 42 to the outer ends of the buttons so as to prevent strands of hair from slipping off the buttons 55 when it is wound thereon.

3

Each of the hair curling members 24 is separably mounted on the clamp 22 by means of a stud 44 which is firmly secured to the arm 26 of the clamp and is provided with a "bayonet" type locking slot 46, as shown in Figure 4. Several of the studs 44 are provided on each clamp to accommodate the respective curling members 24, each stud being slidably receivable in one end portion of the respective curling member, more particularly, of the body 36 of the respective curling member, which body is provided with an inwardly projecting locking pin 48 for reception in the locking slot 46.

It will be apparent from the foregoing that the hair curling members 24 may be applied to the clamp 22 by simply sliding one end portion of the tubular bodies 36 over the respective studs 44 and thereafter rotating the bodies so as to lock the pins 48 in the "bayonet" slots 46, so that the hair curling members are disposed substantially perpendicularly to the plane of opening and closing movement of the arms 26, 28 of the clamp.

When in operation, several strands of hair may be secured adjacent their roots in the clamp and each strand wound around one of the curling members 24, as shown in Figure 6 at 50, so that the strand of hair assumes the form of several separate coils, some of which are disposed on the body 36 while the others are disposed on the buttons 38, whereby the axis of one coil is perpendicular to the axis of the next.

It is to be noted that the coils of hair wound around the curling members do not overlap, that is, each coil consists of only one convolution, thus assuring that the hair in each coil is fully in contact with the curling member and is fully exposed to application of heat, solutions, etc., for proper permanent waving, which is not possible in conventional devices where, because of shortage of space on the curler, convolutions of hair in a coil are necessarily overlapped.

Needless to say, the hair applied to the instant apparatus may be subjected to any one or more varied forms of treatment, such as application of heat, cold waving solutions, chemicals, pre-heating, or the like.

A modified hair curling member is shown in Figure 7 and designated generally by the reference character 60, which may also be used with the clamp 22. The member 60 comprises a tubular body 62 having a plurality of laterally projecting buttons 64 thereon, and while in the member 24 the several buttons 38 are disposed all at one side of the body 36, in the member 60 the buttons 64 are disposed alternately at the diametrically opposite sides of the body 62 as will be clearly apparent.

In a further modified embodiment of the invention which is illustrated in Figure 8 and is designated by the general reference character 70, the tubular body 72 is provided with a pair of laterally projecting, abutting flanges 74 which carry the buttons 76, it being noted that these buttons are not only disposed alternately at the opposite sides of the flanges, but, by virtue of the flanges, the buttons are spaced or shifted laterally from the longitudinal axis of the body 72 so that they do not extend radially from the axis of the body, as in the members 24 or 60. Needless to say, when a strand of hair is wound around the member 70, it is wound under the body 72 and around the buttons, so that it does not cross over the flanges 74.

A still further modified embodiment of a hair 75

4

curling member is illustrated in the accompanying Figures 9-11, inclusive, and is designated generally by the reference character 80, this embodiment being very similar to the embodiment 70 shown in Figure 8, with the exception that the flanges 74 are provided between the buttons 76 with recesses 82 through which the strand of hair may be led as shown at 84 in Figure 11.

The modified embodiment of the hair curling member illustrated in Figures 12-14, inclusive, is designated generally by the reference character 90, this embodiment having an elongated body consisting of a plurality of coaxial sections 92, 94, the sections 92 being rigidly secured by suitable set screws or pins 96 to a supporting shaft 98, while the sections 94 are rotatably mounted on the shaft 98 between the sections 92. Laterally projecting buttons 100 are secured to the several sections, and it will be apparent that by simply rotating the sections 94 on the shaft 98, the buttons on the sections 94 may be adjusted radially with respect to the buttons on the sections 92.

However, means are provided for resisting free rotation of the sections 94 on the shaft 98, these means consisting of a spiral spring 102 which is disposed on the shaft 98 in each section 94 and has one end thereof anchored to the shaft 98 as at 104. The other end 106 of the spring 102 functions as a pawl which engages ratchet teeth 108 provided in the bore of each section 94, so that rotation of the sections 94 is resisted and is possible in one direction only. If desired, the ratchet teeth 108 may be omitted and the end 106 of the spring 102 permitted to frictionally engage a smooth inner wall of the body sections 94, so that the spring functions as an "overrunning" clutch, permitting rotation of the sections 94 in one direction only.

Finally, referring to the modified embodiment of the invention illustrated in the accompanying Figures 15, 16 and 17, this embodiment is designated generally by the reference character 110 and includes in its construction a hair strand receiving clamp 22' having an arm 26' provided with a plurality of keyhole slots 112, whereby a plurality of studs 114 may be separably connected to the arm 26'.

Each of the studs 114 is provided intermediate the ends thereof with an enlarged head 116, a sectionally reduced neck 118 and an additional head 120, the slots 112 being of such dimensions that the head 120 may be passed through the relatively large end thereof, whereupon the reduced neck 118 may be passed into the relatively narrow end portion of the slot, in which manner the several studs 114 may be removably secured in the respective slots 112 of the clamp arm 26', as shown in Figure 16.

The rubber sleeve 30' on the arm 22' may be recessed as indicated at 122, so as to provide clearance for the studs 114, as shown.

Each stud 114 also includes a diametrically reduced, substantially cylindrical stem portion 124 provided with a transverse slot 126 to receive a transversely extending end portion 128 of a coil spring 130 which is positioned on the shank portion 124 of the stud and has a free end 132.

The hair curling members 134 used in this embodiment may be similar to any of the aforementioned members 24, 60, 70, 80 or 90, as long as they include a substantially tubular body portion 136 having either of its end portions adapted for removable positioning on the studs 114.

By passing one end portion of the body 136

over the stud 114, the free end portion 132 of the spring 130 is brought in frictional engagement with the inner surface of the body 136, in which manner the spring 130 will function in the nature of an "over-running" clutch, permitting the body 136 to be rotated in one direction only.

Strands of hair may be wound around the body 136 and the buttons 138 thereon, the arrangement of the angularly offset buttons will facilitate various different arrangements of the wound coils of hair, it being noted that the several hair curling members 134 on the clamp arm 26' may be adjusted relative to each other by rotation about the studs 114, and alternatively, or in addition, studs may be provided in the upper end portions of the bodies 136, so that the bodies may be reversed, end for end, for connection to the clamp arm 26' in a selective manner.

In any event, the hair curling members 134 are sustained in position on the studs 114 by means of a keeper element 140 which consists of a pair of sections hingedly connected together as at 142, the two sections having arcuate recesses or notches 144 to fit the outer surface of the bodies 136. In this manner, the keeper member 140 may be inserted between the bodies 136 as shown in Figure 16, so as to firmly sustain the latter in position on the studs 114 applied to the clamp arm 26'. After strands of hair are wound around the members 134, the keeper member 140 may be readily removed by virtue of the hinge 142.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. A hair curling apparatus comprising a clamp for receiving hair strands, said clamp including a pair of arms pivotally connected to one another at one end, longitudinally spaced supporting means on one of said arms, curling members detachably mounted on said supporting means, said curling members extending perpendicularly from said one arm and having a plurality of laterally projecting, longitudinally spaced buttons thereon, the ends of said curling members being identically formed and selectively mounted on said supporting means, said supporting means including keyhole slots opening toward one another provided on said one arm, said curling members including studs detachably secured to the ends thereof, said studs including heads and reduced necks received in said keyhole slots, means between said curling members and acting upon said curling members to force them away from one another into seating engagement in said keyhole slots.

2. A hair curling apparatus comprising a clamp for receiving hair strands, said clamp including

a pair of arms pivotally connected to one another at one end, longitudinally spaced supporting means on one of said arms, curling members detachably mounted on said supporting means, said curling members extending perpendicularly from said one arm and having a plurality of laterally projecting, longitudinally spaced buttons thereon, the ends of said curling members being identically formed and selectively mounted on said supporting means, said supporting means including keyhole slots opening toward one another provided on said one arm, said curling members including studs detachably secured to the ends thereof, said studs including heads and reduced necks received in said keyhole slots, means between said curling members and acting upon said curling members to force them away from one another into seating engagement in said keyhole slots, said curling members being tubular and said studs being received within the end thereof, coil springs surrounding said studs and being secured at one end thereto, said coil springs being disposed within said curling members and frictionally engaging the walls thereof.

3. A hair curling apparatus comprising a clamp for receiving hair strands, said clamp including a pair of arms pivotally connected to one another at one end, longitudinally spaced supporting means on one of said arms, curling members detachably mounted on said supporting means, said curling members extending perpendicularly from said one arm and having a plurality of laterally projecting, longitudinally spaced buttons thereon, the ends of said curling members being identically formed and selectively mounted on said supporting means, said supporting means including keyhole slots opening toward one another provided on said one arm, said curling members including studs detachably secured to the ends thereof, said studs including heads and reduced necks received in said keyhole slots, means between said curling members and acting upon said curling members to force them away from one another into seating engagement in said keyhole slots, said curling members being tubular and said studs being received within the ends thereof, coil springs surrounding said studs and being secured at one end thereto, said coil springs being disposed within said curling members and frictionally engaging the walls thereof, the inner walls of said curling members being non-circular in cross-section and providing a pawl whereby rotation of the curling members on the studs is possible in only one direction.
